COMBINATION RULE AND SLIDABLE HEAD

Filed June 11, 1935

UNITED STATES PATENT OFFICE

2,085,461

COMBINATION RULE AND SLIDABLE HEAD

John S. Chafee, Providence, R. I., assignor to
Brown & Sharpe Manufacturing Company, a
corporation of Rhode Island

Application June 11, 1935, Serial No. 25,996

12 Claims. (Cl. 33—95)

This invention relates to a rule with a head member movable therealong for testing or laying out purposes; and has for one of its objects the provision of means whereby the relative position 5 of the rule and the head member can be adjusted for securing the desired relation of the two parts.

Another object of the invention is the provision of a lateral adjustment of the rule relative to one 10 of the heads so that the parts may be variously adjusted to suit the convenience of different users.

Another object of the invention is the provision 15 of an aligning or adjusting means so that the head may be moved through different angular positions or adjusted laterally of the rule for securing the desired relative position of the two parts.

Another object of the invention is the provision 20 of a construction whereby the parts may be aligned without the accurate grinding of certain surfaces of the head part which has heretofore been necessary.

Another object of the invention is the provision 25 of a construction which from a manufacturing standpoint may effect a great saving in the manufacture of the parts, such for instance as a provision by which a multiplicity of parts can be ground together.

30 With these and other objects in view, the invention consists of certain novel features of construction, as will be more fully described, and particularly pointed out in the appended claims.

In the accompanying drawing:

35 Fig. 1 is a top plan view of a rule or scale with several different heads mounted thereon which are supplied as a combination set;

Fig. 2 is a fragmental view of a portion of the rule, showing the center head in section as 40 mounted thereon;

Fig. 3 is a sectional view of the center head;

Fig. 4 is a section on line 4—4 of Figure 1;

Fig. 5 is a section on line 5—5 of Figure 3.

45 In the manufacture of a combination rule and centering, testing or truing up heads slidable thereon, it has been necessary to grind the contacting surfaces of the parts including the slot in the head which receives the scale with accuracy in order that a proper position and alignment of the different parts of the assembly may be had. In the case of the grinding of the center head on the scale, it was necessary to grind each surface individually because of the necessity of 50 indexing the head from its first grinding position

about a pivot point which passes through the apex of the right angularly related faces so as to accurately position the second face so that it may be ground in a definite relation with reference to the other ground faces and also so that its apex 5 is at a certain definite position with relation to the surface edge of the slot which slides along the edge of the scale; and I have provided a means whereby much less expensive procedure need be had in the manufacture as the surface 10 of the slot need not now be in a definite relation to the apex or intersection of the right angular faces of the center head, and I may make certain adjustments by reason of two pins so that the slot may be cut deeper and then the ends of these 15 pins which project into the slot serve as guiding points to engage the edge of the scale and cause it to be properly aligned with the apex of the angle by the two right angular surfaces. By reason of these spaced points of contact I may cause 20 an angular relation to be had between the edge of the scale and the right angular surfaces which engage the work, and thus I do not need to accurately align the edges of the slot nor do I need to have a slot at a certain definite angular relation 25 by reason of my adjusting pins. Further, by this arrangement, I can grind a multiplicity of center head surfaces at one position and then turn this multiplicity about a pivot parallel to the apex of the angle formed by the two meeting surfaces and grind the other surface. Thus it is not necessary to grind each center head individually 30 or turn each one about an axis passing parallel to the edge of the slot which formerly engaged the edge of the scale, whereby I am enabled to 35 effect a great saving in the process of the manufacture of the parts as well as obtaining an instrument capable of more extended use; and the following is a more detailed description of the 40 present embodiment of this invention, illustrating the preferred means by which these advantageous results may be accomplished.

With reference to the drawing, I have shown a rule or scale 10 which is provided with a groove 11 extending longitudinally in one surface thereof, preferably in the center thereof with the opposite edges 12 and 13 of this rule parallel to the center groove 11 extending midway between these opposite edges 12 and 13.

Various heads are shown in Figure 1 as 50 mounted on the rule, there being a square head 14, a protractor head 15 and a center head 16 illustrated in Figure 1. Each of these heads has a slot for the reception of the rule 10 and a means 55 for engaging the groove 11 and drawing one edge

of this slot towards the edge of the rule. This invention may be applied to any one of these heads, although it is particularly useful in connection with the center head 16, and I will, accordingly, describe the same in further detail in connection with this center head, although I do not limit myself to its use in this head for any of its functions which may be performed elsewhere.

The center head 16 consists of a body portion 17 with arms 18 and 19 extending therefrom, the surfaces 20 and 21 of which are in right-angularly extending planes or at 90° one to the other. The apex of this angle will be designated generally 22. A slot 23 is cut through the body 16 and one of the arms so as to receive the rule 10. One surface 24 of this slot which has heretofore been required to pass through the apex 22 of the angle or through the intersection of the right angularly extending surfaces 20 and 21 and also in 20 a plane half way between the planes of these two surfaces, is now cut deeper than heretofore so that the surface 24 of the edge of this slot is in a plane which does not pass through the apex of this angle but is rather at one side and also 25 though preferably so it is not necessarily parallel to this plane.

A pair of openings 25 and 26 are bored in the body portion 17 of the head and tapped to receive the threaded pins 27 and 28 which provide bearing surfaces 29 and 30 to engage the edge 13 of the rule 10. These pins are slotted as at 31 so that they may be engaged by a screw driver or the like for adjustment by rotation so as to project one or the other of these further into the slot 35 and thus vary the relative position of the rule in the head, either laterally by moving both pins the same amount to determine whether or not the edge 13 passes through the apex of the angle 22 or to one side thereof for the accommodation 40 of the thickness of a pencil line or the like, or these pins 27 and 28 may be adjusted one more than the other so as to vary the angular relation of the edge 13 with reference to the surfaces 20 and 21 and thus adjust the edge so that it will 45 accurately be located in a plane half way between the plane of the surfaces 20 and 21 or at any other desired position which may be required. These pins 27 and 28 are held in adjusted position by set screws 44 threaded into the body of 50 the head.

In order to draw the edge 13 of the rule towards these pins or bearing points, I provide a pin 35 having a hook end 36 with spaced engaging points to extend into the groove 11. This pin 55 passes through bore 37 in the body and its threads 38 are engaged by a nut 39 on the outer end of the pin 35 which when turned to move the nut inwardly, abuts the body 17 as at 40 so as to move the body and the edge of the rule in opposite 60 directions upon such adjustment. This nut has a knurled handle 41 for affording a more secure grasp, while a spring 42 is provided for tending to move the parts in the opposite direction and for holding them tight although yieldable as more 65 fully explained in Patent No. 1,529,209, with which I am familiar, and which is owned by my assignee.

By this arrangement I do not have to accurately cut slot 23 or even finish it, but can obtain 70 my adjustment by means of the threaded bearing pins, thus permitting grinding of a multiplicity of centering heads to obtain the surfaces 20 and 21 at right angles irrespective of their relation to the edge 24 of the slot, which has not heretofore been possible where the accuracy of 75

the surface 24 with reference to the surfaces 20 and 21 was essential.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In combination, a rule, a head having a slot therein for slidably receiving the rule, and means in said slot for bearing against an edge of the rule at a plurality of spaced portions therealong and movably mounted with reference to the head for movement against said edge portion of the rule for laterally and also angularly adjusting the position of the head with relation to the rule.

2. In combination, a rule, a center head having a slot therein for slidably receiving the rule and provided with right angularly related work engaging faces, and means for angularly adjusting said head as a unit with reference to said rule to position the edge of the rule in an angular relation between the work-engaging faces.

3. In combination, a rule, a head having a slot therein for slidably receiving the rule, spaced bearing members for engaging against an edge of said rule and movably mounted in said head and protruding into said slot, and means to secure said rule laterally and angularly with reference to said head and seated upon said bearings.

4. In combination, a center head having right angularly related work engaging faces with a slot therein for receiving a rule with one edge passing substantially through the intersection of said faces, a rule in said slot having a groove in one face thereof, clamping means engaging said groove to draw the rule towards one edge of the slot, and adjustable bearing means movably mounted in said head and projecting through said slot edge to engage an edge of the rule, said means being adjustable for laterally shifting the rule with reference to said head for shifting the edge of the rule with reference to the intersection of the faces.

5. In combination, a center head having right angularly related work engaging faces with a slot therein for receiving a rule with one edge passing substantially through the intersection of said faces, a rule in said slot having a groove in one face thereof, clamping means engaging said groove to draw the rule towards one edge of the slot, and adjustable bearing means movably mounted in said head and projecting through said slot edge to engage an edge of the rule, said means being adjustable for angularly shifting the rule with reference to said head that it may bear a different relation to said right angular faces.

6. In combination, a center head having right angularly related work-engaging faces with a slot therein for receiving a rule with one edge passing substantially through the intersection of said faces, a rule in said slot having a groove therein, means engaging said groove to draw the rule towards one edge of the slot, and bearing means projecting through said slot edge to engage the rule, said means being adjustable for laterally or angularly shifting the rule with reference to said head that it may bear a different relation to said right angular faces.

7. In combination, a center head having right angularly related work-engaging faces with a slot therein for receiving a rule with one edge passing substantially through the intersection of said

faces, a rule movably mounted in said slot, means to draw the rule towards one edge of the slot, and spaced bearings movably mounted in said head and projecting through said slot edge to engage the rule, and means for moving said spaced bearings to vary the relative position of the rule and head.

8. In combination, a center head having right angularly related work-engaging faces with a slot 10 therein for receiving a rule with one edge passing substantially through the intersection of said faces, a rule movably mounted in said slot, means to draw the rule towards one edge of the slot, spaced pins movably mounted in said head and 15 projecting through said slot edge to engage the rule, and means for moving said spaced pins to vary the position of the rule and head.

9. In combination, a center head having right angularly related work-engaging faces with a slot 20 therein for receiving a rule with one edge passing substantially through the intersection of said faces, a rule movably mounted in said slot, means to draw the rule towards one edge of the slot, spaced threaded pins projecting through said slot 25 edge to engage the rule and threadingly mounted in the head to vary the position of the rule and head, and means to secure said pins in an adjusted position.

10. In combination, a center head having right angularly related work-engaging faces with a slot 30 therein for receiving a rule with one edge passing substantially through the intersection of said faces, a rule in said slot having a longitudinal groove on a side face thereof, clamping means 35 engaging said groove to draw the rule towards one edge of the slot, and spaced pins movably mounted in said head and projecting through said slot edge to engage the rule, means for moving

said spaced pins to vary the position of the rule and head, and means in said head to secure said pins in position therein.

11. In combination, a head comprising a body portion having a pair of right angularly inclined arms extending outwardly therefrom from a common intersection and with opposed work-engaging surfaces thereon, said body portion being integrally joined at the apex of said intersecting arms and extending outwardly therefrom in a plane passing through said apex and between the planes of the arms, one of said arms and said body portion having a rule receiving slot the bottom surface of which is disposed at one side of said apex and lies in a plane which is other than 15 coincident therewith, said body having a hole therein which is disposed transversely thereof and cross-wise with respect to said slot, a rule movably mounted in said slot having a central longitudinal groove on a side face thereof, a 20 clamping pin in the hole having an inner hook end carrying spaced engaging points to engage said rule groove, means on the outer end of said pin to clamp the pin in adjusted position, spaced bearing pins adjustably mounted in said head 25 and projecting through said slot edge to engage the bottom edge of the rule, and means for adjusting said pins to shift the rule laterally or angularly with reference to said head.

12. In combination, a rule, a head having a slot 30 therein for slidably receiving the rule, and means in said slot for bearing against an edge of the rule and movably mounted with reference to the head for laterally and also angularly adjusting the position of the head with relation 35 to the rule.

JOHN S. CHAFEE.
